(57) **CLAIM**

The ornamental design for a combined label for seal, as shown and described.

DESCRIPTION

FIG. 1 is a front perspective view of the combined label for seal showing my new design;

FIG. 2 is a front view thereof;

FIG. 3 is a top view thereof;

FIG. 4 is a left side view thereof, the right side view being a mirror image thereof; and,

FIG. 5 is a front perspective view of the combined label for seal being used with an embosser.

The broken lines in the drawings illustrate environment and form no part of the claimed design.
